UNITED STATES PATENT OFFICE.

FREDRICK DANNER, OF HOME CITY, AND THOMAS P. EGAN, OF CINCINNATI,
ASSIGNORS TO THE EGAN COMPANY, OF CINCINNATI, OHIO.

GRINDING-MACHINE.

SPECIFICATION forming part of Letters Patent No. 350,351, dated October 5, 1886.

Application filed January 22, 1885. Serial No. 153,654. (No model.)

To all whom it may concern:

Be it known that we, FREDRICK DANNER and THOMAS P. EGAN, residents of Home City and Cincinnati, respectively, in the county of 5 Hamilton and State of Ohio, have invented certain new and useful Improvements in Grinding-Machines, of which the following is a specification.

Our invention relates to an improvement in 10 grinding-machines.

The object of our invention is to provide positive means for adjusting the pitch and feed of the carriage which carries the material to the stone or emery-wheel for grinding without 15 interference from lost motion.

Another object of our invention is to provide convenient and positive means for the varying adjustments of the stock holding the tool to be ground.

20 Other features of our invention will be fully set forth in the description and claims.

Figure 1 is a top plan view of our improvement. Fig. 2 is a section on line *x x*, Fig. 1. Fig. 3 is a detail view of the stock-adjusting mechanism. Fig. 4 is a perspective view of the frame. Fig. 5 is a skeleton plan view of the longitudinal slide-frame. Fig. 6 is a perspective view of one of the weighted arms. Fig. 6^a is a detail cross-section and elevation 25 of the arms, showing their connection with the shaft. Fig. 7 is a perspective view of the entire machine. Fig. 8 is a front elevation of the same. Fig. 9 is a detail view showing the rack and driving-pinion.

30 A represents the frame of the machine. It is preferably cast hollow and provided with openings *a*.

B represents gains cut in the sides of the top of the frame, in which the slides C C of the 40 longitudinal adjustable frame work.

b b represent ways on which the transverse reciprocating carriage F moves.

c c' represent extensions rigidly connected to one of the slides C and one of the ways *b* 45 on which the driving mechanism for moving the tool is mounted.

C represents the main driving-pulley, mounted on the main shaft 4. *C'* represents a loose pulley mounted on the outer end of said shaft. 50 *2* represents the transmitting-pulley, also mounted on said shaft 4.

3 represents a transmitting-pulley on the opposite end of shaft 4, vertically under the pulleys 6 7 8.

D represents a grinding-stone or emery-wheel mounted on a shaft, 5. A belt passes around pulleys 3 7, the latter running loosely on the shaft 9, which shaft is journaled on the slides C and extension arm *c*. 8 represents a driving-pulley keyed upon said shaft 9 on one 60 side of pulley 7. 10 represents a bevel-gear keyed upon the outer end of said shaft 9.

11 represents a bevel-gear keyed upon sleeve 12, which sleeve journals on shaft 9. 6 represents a driving-pulley attached to said 65 sleeve 12.

13 represents a bevel-gear journaled on shaft 14, which meshes with and is driven by gears 10 and 11 in different directions, one of which bevels runs as an idler, while the other is a 70 driver.

15 represents a spur-gear keyed upon shaft 14 and meshing with gear 16, keyed upon shaft 17. On the outer end of shaft 17 is keyed the spur-gear 18, which meshes with the teeth 75 of rack 19 on the under side of the carriage F, as shown in Fig. 9.

G represents an oscillating stock, which is journaled on centers to studs *g*, which project up from the table, as shown in Figs. 1, 7, and 8. 80

f represents a slotted arm rigidly secured to the stock G, projecting forward.

e represents a supporting-arm secured to the table F, provided with a pin or bolt working in the slot of arm *f*, to which it is secured 85 by a set-screw.

The slides C C, working in the gains B of the frame A, are adjusted in or out in any desired fixed position, so as to set the stock G in the desired relation to the grinder D by the following means:

20 represents a shaft journaled on the frame A. It is provided with a grooved collar, *i i*, rigidly secured to the shaft, as shown in Fig. 3.

21 represents a screw-thread chased on the 90 outer end of the shaft, which passes loosely through the frame A and taps into a ledge, H, which projects downward from the under side of one of the ways *b*.

22 represents a jam-nut for securing shaft 100 20 in any desired adjustment.

23 represents a hand-wheel for turning shaft

20, to draw it out or in for moving the slides C C and the table F out or in for adjusting the stock G to the grinder.

In order to prevent lost motion of the slides 5 C in the gains B, and to hold the table F fixed in any desired adjustment, as well as to gage or limit the inward movement of the table F and ways b, we have provided the following means:

10 I J represent weighted arms, each of which is the counterpart of the other, which are provided with an offset, M, on the upturned arm above the pivots L, so as to engage with the grooved collar or collars i i. A weight, N, is 15 placed upon the outer end of arm I, which draws the table F and slide C inward and holds them in that position for work; but to take up lost motion of the arm I in the collars i i the arm J is also weighted by weight n, and 20 adjusted near the inner end of the arm. Weight N holds the stock and tool to the fixed inward adjustment.

To limit the inward movement of the table we have provided the adjusting-screw 24, 25 which taps through lug 29 on flange H, that is attached to the outer way b. The inner end of the screw 24 rests against the frame A.

25 represents the jam-nut for holding the adjusting-screw 24 in its fixed position.

30 The table F, which carries the stock G laterally across the face of the grinder D, is operated in the following manner: The knife or tool is attached to the stock G. It is set at the desired angle by the adjusting-arms e f. 35 The grinder D is driven by a belt passing over pulleys 1 2.

The carriage is moved laterally by gears 10 11 13, driven by a belt passing over the pulleys 3 and 6 7 8, which is shifted onto the 40 pulley 8 or 6 in the following manner: P represents a belt-shifting arm keyed upon rod

27. R represents a rectangular opening made in arm P, through which the belt which drives the wheels 6 7 8 runs loosely. 26 represents 45 a lever hinged or pivoted to rod 27 on its inner end, and connected to the cross-piece

28 by pivot 28, secured to the frame, and its front end projecting under the table and ways through an opening in the flange H. 30 31

50 represent adjustable fingers secured to the table, which alternately shift the lever 26 and the belts from pulleys 6 to 8, or vice versa, by the reciprocation of the carriage. Pulley 8 drives shaft 9, transmitting power

55 through bevels 10 to 13 to shaft 14, driving spur-gear 15 in one direction, which spur transmits power to gear 16, shaft 17, and gear 18, which engages with the rack-teeth and moves the table in one direction. The reverse move-

60 ment of the table F is made by shifting the belt on pulley 6, which drives sleeve 12 and spur-gear 11 attached thereto, transmitting power to bevel 13, shaft 14, and spur 15, turning them in the reverse direction, and like- 65 wise gear 16, shaft 17, and spur-gear 18, which moves or reciprocates table F also in the op-

posite direction.

We have found by experience that the means herein described and shown adjust the tool to the grinder accurately, and hold it to a fixed position without any lost motion. 70

The counterpoise n, acting upon the separate collar i, exerts a constant force in counteraction of the weight N, and the two levers being entirely distinct from each other and 75 independent in action, this force is sufficient, when the counterpoise is properly placed, to instantly relieve the pressure upon the grinding-periphery the moment the action of the weight N is from any cause suspended. 80 Moreover, the action is the same in kind, though varying in degree, when the gravity of weight N is in part only interrupted from any causes. The result is, that all lost motion or backlash is avoided, and all wear by 85 which the same is produced is compensated by the construction shown, so that the long-continued use of the machine does not tend to cause inaccuracy due to the backlash produced by the wear of the parts. 90

We claim—

1. The combination, in a grinding-machine, of the frame A, having gains B, the adjustable slides C, fitting in said gains, extensions c c', and ways b, connected to said slides, reversing-gears 10, 11, and 13, supported in said extensions, and the connected driving mechanism, substantially as described. 95

2. The combination, with the frame A and adjustable slides C, mounted thereon, of the driving and reversing mechanism mounted upon and moved with said frame, and consisting of the gears 10 and 11, the interposed gear meshing with said gears, and the tight pulleys 6 and 8 and loose pulley 7, the former 105 for operating the driving-gears alternately, while the latter serves as an idler, substantially as described.

3. The combination, with the extension H, of table C, having ways b, the shaft 20, an adjusting screw and nut connecting said shaft and extension, and weighted arms I J, substantially as described. 110

4. In combination with the ways b and slide-frame C, carrying said ways, the adjusting-rod 20, the weighted arms I J, engaging said rod, and the set-screw 24, resting against the frame A, to limit the inward movement of the ways, substantially at specified. 115

5. In combination with the adjusting-shaft 120 20, the weighted levers I J, adapted to engage and hold the shaft 20 in its desired fixed position without lost motion, substantially as specified.

In testimony whereof we have hereunto set 125 our hands.

F. DANNER.
THOS. P. EGAN.
